CLAIM

The ornamental design for an interlocking frame toy brick as shown and described.

DESCRIPTION

FIG. 1 is a top perspective view of an interlocking frame toy brick.

FIG. 2 is a front plan view of the interlocking frame toy brick.

FIG. 3 is a back plan view of the interlocking frame toy brick.

FIG. 4 is a side plan view of the interlocking frame toy brick.

FIG. 5 is a second, side plan view of the interlocking frame toy brick.

FIG. 6 is a top plan view of the interlocking frame toy brick.

FIG. 7 is a bottom plan view of the interlocking frame toy brick.

FIG. 8 is a bottom perspective view of the interlocking frame toy brick.

FIG. 9 is a top perspective view of a second embodiment of the interlocking frame toy brick.

FIG. 10 is a front plan view of the second embodiment of the interlocking frame toy brick.

FIG. 11 is a back plan view of the second embodiment of the interlocking frame toy brick.

FIG. 12 is a side plan view of the second embodiment of the interlocking frame toy brick.

FIG. 13 is a second, side plan view of the second embodiment of the interlocking frame toy brick.

FIG. 14 is a top plan view of the second embodiment of the interlocking frame toy brick.

FIG. 15 is a bottom plan view of the second embodiment of the interlocking frame toy brick; and,

FIG. 16 is a bottom perspective view of the second embodiment of the interlocking frame toy brick.

(Continued)

The broken lines in the figures show features of the interlocking frame toy brick that form no part of the claimed design.
